Jay W. Powers

United States Patent Office.

JAY W. POWERS, OF EVANSTON, ILLINOIS.

Letters Patent No. 65,601, dated June 11, 1867; antedated May 28, 1867.

IMPROVEMENT IN HINGES.

The Schedule referred to in these Letters Patent and making part of the same.

TO WHOM IT MAY CONCERN:

Be it known that I, JAY W. POWERS, of Evanston, in the county of Cook, and State of Illinois, have invented a new and useful Improvement in Hinges; and I do hereby declare that the following is a full, clear, and exact description of the construction and operation of the same, reference being had to the annexed drawings, making a part of this specification, in which—

Figure 1 is a perspective view.

Figure 2 shows the parts or segments of which it is composed.

Figure 3, a transverse section of the hinge when in operation; and

Figure 4, the same when closed.

A B and C represent the three parts of a triplicate hinge, united at a and a' by the pins d and d' , inserted into their appropriate thimbles, in the usual manner of joining butt-hinges. A and C are perforated with holes $l l l l$, $l l l l$, for screws to secure the hinge in its application in use, A being joined to B at a , and B to C at a' , so that when closed the part B is folded between the others. The part A is provided with a fossa or depression, c , and at the sides of this fossa thimbles b b , through which a pin is inserted. The part B has a slot or sinus, f , and thimbles e e also for a pin. The part C has a slot, h . D is a cam for regulating the movements of the other parts; it consists of a body, n , and a head, o ; m is a pin projecting from the sides of the body n , at its end; i is a slot in the head o , having a curved or parabolic form; k is a round hole. Uniting these parts as shown in fig. 3, the cam D is passed through the slot f , and secured to the part B by the pin passing through thimbles e e and the hole k , while the slot i receives the pin passed through the thimbles b b on the part A, the head resting in the fossa c , the small end of the body n being passed through the slot h on the part C, the pin m holding it in its place, and, as the hinge is opened and shut, sliding behind, or in a groove on the part C. When the hinge is shut, the parts rest in the position shown in fig. 4.

It will readily be perceived that the operation of the cam is such that when the hinge is opened at the joint a' , the head of the cam sliding in the fossa c , forces the part B away from the part A, allowing the door E to swing clear from its post, frame, or easing, F, the corner, taking the direction shown by the dotted lines p p , as shown in fig. 1; and on closing it the pin passes through the thimbles b b , and the slot i forces the parts A and B together, so that when applied to a door or other thing to which it may be applicable, it is not necessary that the hinge come to the surface at either side, but may be placed at a distance therefrom, within the wood or other material of which the door or its frame is made, and hence when the door is closed be entirely concealed or invisible.

I do not claim the invention of the triplicate hinge, for that may have been made before; but what I claim as my invention, and desire to secure by Letters Patent, is—

The cam D, applied to a triplicate hinge, constructed and operating substantially as and for the purposes herein set forth.

JAY W. POWERS.
